CONVEYER MECHANISM

Edward N. Michna, Detroit, Mich., assignor to
Evelyn Michna, Detroit, Mich.

Application January 25, 1943, Serial No. 473,457

2 Claims. (Cl. 198—184)

This invention relates to endless belt conveyer mechanisms, and may be considered a continuation in part, of the invention disclosed in my co-pending application, S. N. 470,721, filed December 31, 1942.

An object of the invention is to generally improve endless belt conveyers, and particularly to improve the device disclosed in my co-pending application referred to above.

The handling of certain types of materials, particularly heavy materials, on an endless belt conveyer, constructed and arranged as disclosed, in my co-pending application, introduces certain problems of friction, which would not otherwise be present. It is therefore, one of the objects of this invention to provide a device, which will greatly overcome the friction, which is developed in such cases.

Another object of the invention is to facilitate the travel of the conveyer belt over the directional change members in such manner that there is no tendency for the belt to spiral on the members, as would happen when a revolving cylinder is used.

The foregoing and other objects and advantages of the invention will become more apparent as the description proceeds, reference being made from time to time to the accompanying drawing, in which:

Fig. 1 is a fragmentary, perspective view of a device embodying my invention.

Fig. 2 is a section taken on the line 2—2 of Fig. 1.

Fig. 3 is a section taken on the line 3—3 of Fig. 1.

Referring now more particularly to the drawing, it will be understood that in the embodiment herein disclosed, my improved device consists of the endless conveyer belt 7, which is mounted and driven as disclosed in my co-pending application indicated above.

In this embodiment my angularly positioned directional change members, 8 and 9 are cylindrical in shape and are preferably made of hard wood, and do not rotate, but are provided with a plurality of ball bearings 10, which are encased in suitable sockets or raceways 11, which in turn are recessed in the surfaces of the members 8 and 9. It will be noted that the ball bearings 10, are permitted to rotate in their sockets,

but are not permitted to travel laterally or longitudinally of the members 8 and 9. With this arrangement the surface of the belt 7, is supported in a non-frictional manner, on a plurality of contact members, which are free to rotate, but, which will not impart a spiral motion to the belt 7.

For purposes of illustration, I show in Fig. 1, the raceways 11, extending in a circumferential direction on the member 8, whereas they extend in a longitudinal direction on the member 9. In each instance, however, the raceways 11, are recessed in the members 8 and 9, so that the balls 10 extend slightly above the surfaces of the members 8 and 9. Inasmuch as the members 8 and 9 are preferably made of a hard wood, it is a comparatively easy matter to groove them, as at 12, and press fit the raceways 11 into the grooves. When the raceways 11 are once installed and the belt 7 is in operating position the raceways 11 cannot be dislodged, and the operation of the device tends to make them more secure. In order to provide lubrication for the balls 10, I provide grease connections 13, which connect through passageways 14, with the various balls 10. A minimum of lubrication, however, is recommended because of the direct contact of the balls 10 with the belt 7.

It will be understood that other modifications may be made in the arrangement of parts, all of which is intended to be within the contemplation of the invention and the scope of the appended claims.

Having described my invention what I claim and desire to secure by Letters Patent is:

1. In a device of the character described including an endless belt and cylindrical direction change elements for said belt, the combination of a plurality of raceways positioned in the surfaces of said cylindrical elements, ball bearings in said raceways, and means for lubricating said ball bearings.

2. A direction change device for an endless belt conveyer, comprising a substantially cylindrical element having a plurality of ball bearing members arranged in its surface and adapted to movably support the endless belt conveyer, and means to lubricate the said ball bearing members from a position beyond the edge of the endless belt.
